NONSIPHONING SWIMMING POOL
TREATMENT SYSTEM

Roy Blair Everson, Chicago, Ill.

Application April 22, 1936, Serial No. 75,860

4 Claims. (Cl. 210—11)

This invention relates to a new and improved re-circulating system for swimming pools and similar devices. At the present time in swimming pool construction it is uniform practice to re-circulate the water in the swimming pool, passing it through some kind of purification system or other. Frequently the re-circulated water is passed through an ultra violet ray purifying system. Frequently it is passed through filters and similar devices. Very often it is passed through some mechanism whereby it is "doctored" with a suitable purifying solution. In all of these cases provision must be made to introduce into the system at some point in the course of re-circulation fresh water from the main or city supply. Of course, it should be understood that very frequently only a small amount of new water need be injected into the system in the course of many hours of operation.

This necessity for introduction of new water has precipitated a very serious sanitation difficulty. In all apparatuses, such as swimming pools, bathtubs, sinks, drains and the like, much difficulty has been encountered due to the fact that there is a tendency for the impure water contained in the receptacle or device to be siphoned back into the main water supply system through whatever means is used for the introduction of fresh water from the main. In recent months this difficulty has been much publicized in the case of bathroom appliances. City health authorities throughout the country are presently devising special health regulations and specifications to overcome this danger.

It is an object of the present invention, therefore, to overcome these difficulties in connection with swimming pool re-circulating systems; to provide means for the introduction of fresh water into a swimming pool re-circulation system without possibility of having the same siphoned back into the water main; and to provide new and novel means for the introduction of purifying solutions without danger of siphoning back.

Numerous other objects and advantages will more fully appear during the course and progress of the following specification.

Figure 1 is an elevation view of a preferred embodiment of the present invention.

Figure 2 is a schematic arrangement showing the present invention in association with a swimming pool.

The preferred embodiment of the present invention shown in Figure 1, comprises a re-circulation pump 1 which has an intake 2 and an out-

let 3. Coupled to the intake of the pump is a supply line 4 through which the water withdrawn from the swimming pool for re-circulation may flow downwardly into the pump. Coupled to the outlet 3 of the pump 1 is a swimming pool return line 5 through which the water withdrawn and re-circulated is returned to the swimming pool. At this point of juncture between the return line 5 and the outlet 3 of the pump 1 is a take-off 6. Coupled to this take-off 6 is an injector supply line 7. This injector supply line 7 should be of considerably smaller diameter and capacity than the return line 5. The injector supply line 7 passes around to the intake side of the pump where it is coupled to one side 8 of the injector 9. The other side 10 of the injector 9 is coupled to a throat pipe 11 which passes through a coupling 12 into the pump intake. It should be noted that this throat pipe 11 runs substantially past the point 15 of juncture between the pump intake and the supply line 4. The side arm portion 13 of the injector 9 is coupled to a hose 14 which may lead off to fresh water supply, or to fresh water supply and reagent, or to reagent solution alone, depending upon the type of purifying system involved.

The hose 14, as shown in Figure 2, passes to a tank 15. This tank 15 is provided with an overflow 16 which is adapted to maintain a 30 level of liquid in the tank 15 at a certain height. The tank 15 is supplied with fresh water, or solution in fresh water, or whatever may be necessary through the line 17 which is controlled by the float ball valve mechanism 18. 35 It should be noted that the termination 19 of the line 17 is located at a substantial distance below the top of the tank 15 and above the highest possible liquid level in that tank. As shown in Figure 2, the swimming pool supply line 4 40 is connected to the swimming pool 20. The swimming pool return line 5 is connected to the swimming pool at some suitable point higher than the lowest point of the pool, as shown in Figure 2. If necessary a valve 21 may be inserted in 45 the hose 14 whereby to control the amount of fluid passing therethrough.

In operation the pump will withdraw a substantially large amount of swimming pool water through the supply line 4 into the intake of the 50 pump system and thereby increase the pressure thereof to return the same and force this water out through the outlet 3 into the return line 5. A small amount of this liquid heat created by the pump is diverted through the injector supply 55

line 7 and passed around into the injector 9 through the intake side 8 of the injector. In passing therethrough this fluid heat creates a suction in the side arm 13 of the injector 9 which 5 suction draws fluid through the hose 14 from the tank 15. The amount of fluid drawn through this hose may be regulated by the valve 21. This fluid is drawn through the side arm 13 of the injector 9 and caused by the action of the said 10 injector to intermingle with the fluid passing through said injector. The combined fluids, therefore are injected into the throat 11 and thence into the intake of the pump where a complete admixture with the swimming pool water 15 is accomplished. Thus if merely fresh water is desired, fresh water may be allowed to run into the tank 15 through the line 17 until the proper level is reached. The supply will be shut off by the float ball valve mechanism 18. Any excess 20 of liquid in this tank will tend to overflow through the overflow 16 and pass off to the sewer. When the level in the tank gets too low obviously the float ball valve mechanism will cause the valve to open and water will be permitted to flow 25 into the tank through the line 17 until the desired level is again reached. Since the hose 14 is opened into the tank and controlled only by the valve 21 it is obvious then that whenever the valve 21 is open and the pump operating, the 30 suction created in the hose 14 by the injector 9 will cause the fluid in the tank 15 to flow therethrough and into the pump system whence it is introduced into the swimming pool system proper.

35 It will be observed that if anything happens to the pump, or the pump is shut down, or some accident takes place whereby these conditions may be produced, the possibility of siphoning will be entirely overcome by reason of the fact that 40 the injector mechanism, which is responsible for the introduction of fresh water or solution into the swimming pool system, is rendered inoperable at the instant the pump becomes inoperable.

A second element of protection is provided in 45 the overflow 16. If for any reason swimming pool water gets into the hose 14 and tends to flow back into it and thence into the tank 15, the only thing that can happen would be that the level in the tank would be raised above the 50 opening into the overflow line 16 so that any water running back into this tank from the swimming pool would be drained off through this overflow line.

It is thought that the invention and numerous 55 of its attendant advantages will be understood from the foregoing description and it is obvious that numerous changes may be made in the form, construction and arrangement of the several parts without departing from the spirit 60 or scope of the invention, or sacrificing any of its attendant advantages, the form herein described being a preferred embodiment for the purpose of illustrating the invention.

What is claimed as new and desired to be 65 secured by Letters Patent is as follows:

1. In a swimming pool water re-circulation system, a pump having an intake and an outlet, said pump being connected to the withdrawal side of the re-circulation system at its intake side 70 and connected to the return side of the re-

circulation system at its outlet side, injector means for introducing additional fluids into the system in combination with the inlet side of the pump, a supply tank for said additional fluids, supply tank conduit means connecting the injector to the supply tank for feeding additional fluid to the injector, an overflow conduit in the tank adapted to limit the maximum liquid level in the tank, and fresh fluid supply means for said tank having its mouth located a substantial distance above the overflow means.

2. In a swimming pool water re-circulation system, a pump having an intake and an outlet, said pump being connected to the withdrawal side of the re-circulation system at its intake side and connected to the return side of the re-circulation system at its outlet side, injector means for introducing additional fluids into the system and connected in an auxiliary line arranged in parallel relationship with the pump, a supply tank for said additional fluids, said injector being actuated by the re-circulation system to forcefully draw additional fluid from the supply tank conduit and inject it into the system, an overflow conduit in the tank adapted to limit the maximum liquid level in the tank, and fresh fluid supply means for said tank having its mouth located a substantial distance above the overflow means.

3. In a swimming pool water re-circulation system, an efflux means, a return means adapted to return water from the efflux means to the pool, pressure-raising means connected therebetween, auxiliary tank means, means for introducing fresh water into said auxiliary tank means, said last named means being disconnected from the fluid in the system, an overflow conduit in the auxiliary tank means to limit the maximum liquid level, and injector means fed by the auxiliary tank means, said injector means being combined with the pressure-raising means and having a throat and a suction arm connected with the throat and a conduit connecting said suction arm with the auxiliary tank to forcefully draw fresh water from said tank when the pressure-raising means is actuated, said injector having relatively small passages communicating with the pressure-raising means whereby to restrain back-flow into the tank upon cessation of the action of the pressure-raising means.

4. In a swimming pool water re-circulation system, a pump having an intake and an outlet, said pump being connected to the withdrawal side of the re-circulation system at its intake side and connected to the return side of the re-circulation system at its outlet side, injector means for introducing additional fluids into the system and connected in an auxiliary line arranged in parallel relationship with the pump, a supply tank for said additional fluids, said injector being actuated by the re-circulation system to forcefully draw additional fluid from the supply tank conduit and inject it into the system, an overflow conduit in the tank adapted to limit the maximum liquid level in the tank, and fresh fluid supply means for said tank operated by a float ball valve whereby normally to maintain a constant level in the tank.
